UNITED STATES PATENT OFFICE

WILLIAM A. OWEN, OF AKRON, OHIO

HEEL FOR FOOTWEAR

Application filed January 26, 1929. Serial No. 335,158.

This invention relates to heels for footwear and particularly what are termed "high heels" for women's shoes.

The general purposes of the invention are 5 to provide a strong, light heel which will not split or crack in application to the shoe or in use, and to provide a heel which has a resilient lift integrally secured thereto but which can be removed for replacement by 10 another lift when it is worn out.

The foregoing and other purposes of the invention are attained in the heel illustrated in the accompanying drawings and described below. It is to be understood that the invention is not limited to the specific form 15 thereof shown and described.

Of the accompanying drawings,

Figure 1 illustrates a longitudinal section 20 through the heel portion of a shoe equipped with a heel embodying the invention; and

Figure 2 is a section on line 2—2 of Figure 1.

The improved heel comprises a body portion 1 of hard, comparatively rigid, cellular rubber or equivalent material provided with 25 an integral veneer 2 of comparatively hard, solid rubber or its equivalents which can be colored by compounding to match the color of the shoe and can be highly polished or 30 which can have a covering of suitable material secured thereon as in the case of the wooden heel.

Extending down in the shank of the heel 35 there is embedded in the body portion a strong light tube 3 which may be of some light metal such as aluminum. This reinforces the shank of the heel and is especially desirable for use in that type of extremely high, small-shanked heel referred to as 40 "French heels" to prevent breakage.

A rubber lift 4 of comparatively soft, tough rubber is vulcanized, preferably as a single operation, with the body of the heel and is thus integrally bonded thereto.

45 It is understood that the heel above-described may be made by methods well-known in the rubber industry which may include the steps of compounding rubber to vulcanize hard and with a blowing agent to make 50 it cellular to provide the body portion 1, in-

corporating the reinforcing tube 3 therein, enclosing the body portion 1 in a veneer 2 of rubber adapted to vulcanize hard, semi-vulcanizing this assembly, and finally completing the cure of the assembly and curing the lift 4 thereto as a single operation.

Because of the different degrees of hardness to which the body of the heel and the lift are vulcanized, it is possible to pull a worn lift off the heel and to leave a substantially smooth surface on the bottom of the heel on which a separate lift may be nailed.

The heel is nailed to the upper of the shoe by the nails 5 which are securely held in the cellular rubber body 1. This body being grainless, it has no tendency to crack as the nails disrupt only those cells through which they pass.

It will appear from the foregoing that a strong, light and effective heel construction 70 has been provided by the invention. Obviously modifications of the invention may be resorted to without departing from the spirit thereof or the scope of the appended claims.

What is claimed is:—

1. A high heel for footwear comprising a body portion of hard, cellular rubber, a reinforcement comprising a metal tube extending down through the shank thereof, 80 said tube being completely supported in said cellular rubber, an integral veneer of hard rubber about the body portion, and a lift of comparatively soft rubber vulcanized to the bottom of the heel.

2. A high heel for footwear comprising a body portion of hard, cellular rubber, a rigid metallic reinforcement extending down through the shank thereof and completely supported in said cellular rubber, an 85 integral veneer of hard rubber about the body portion, and a lift of comparatively soft rubber vulcanized to the bottom of the heel.
